SLOTTED WINGED CYLINDRICAL ANTENNA

Andrew Alford, Cambridge, Mass.

Application June 14, 1948, Serial No. 32,752

12 Claims. (Cl. 250—33)

1

The present invention relates to ultra high frequency radio antennas with a directional pattern in which the backward radiation in a polar diagram pattern has a decreased radiation as compared to the forward sector over a desired sector of arc.

In the present invention one of the desired types of patterns produced is that of a cardioid having a very low radiation over a wide cycle of backward directions, the backward direction in the present invention referring to the sector of arc in the polar diagram where the radiation is least. According to the present invention the center of this sector may have a very low radiation for some 40° or less, increasing gradually to a uniform constant amplitude of radiation in the forward sector.

The present invention is particularly useful and applicable for television broadcasts under conditions where two cities such as A and B some fifty miles apart both have stations operating on channels adjacent to each other. If, for instance, city A has several television stations and all channels which can be assigned to city B without resulting in interference with stations in city A have been assigned, the system of the present invention will make it possible by use of directional antenna according to the present invention to assign an adjacent channel to the station at city B so that operation without interference can be effected. For example: channel 9 can be used in city B in spite of the fact that channels 8 and 10 are already assigned and used in city A.

In the present invention a slotted cylinder with metallic wings is preferably used. This type of antenna alone has a radiation pattern of the desired shape in a forward direction but fails in the backward sector which normally is only about 10 db below the maximum in the forward direction. The desired pattern requirements for the back lobe should be about 35 db below the maximum so that the slotted cylinder with the metallic wings will not alone suffice. If a large metal sheet is placed in back of the wings of the antenna, some suppression of the back lobe is obtained. However the amount of suppression does not appear sufficient and in addition to this, the size of the sheet would necessitate additional structural support comparable in size for the antenna proper. As contrasted with this arrangement the one of the present invention employs two auxiliary driven elements in addition to the main driven antenna with proper adjustment of amplitude and phase for the auxiliary driven elements so that the total radiation directly back-

wards is reduced to the desired low value. A consideration of the slotted cylindrical antenna with outwardly extending wings shows that the voltage across the slot originates a wave which travels outward along the wings in a direction perpendicular to the cylinder and that when the wave arrives at the edge of the wing, some of the energy is reflected back towards the slot and some travels around the edge in such a way as to keep the ends of the electrical lines of force normal to the plane of the wings. The energy which travels around the edge of the wings causes the back lobe. The field configuration near the edges can be considered as two Huygens' sources which radiate in all directions. The amplitude and phase of these sources are dependent on the width of the wing. If the structure is symmetrical, the two Huygens' sources are in the same phase with each other and their contribution add in the direction of 180° that is in the backward direction bisecting the angle between the two wings. At a deviation angle δ from 180° there is a difference in path length between the radiations from these virtual sources. At an angle δ this path difference is a half wave length. At this angle there is a null. At an angle greater than δ the total field increases. As angle δ approaches 90° the field of the main slot becomes predominant with the smaller effect of the two edges superimposed. The angles δ may be assumed to be a reference angle deviating from the 180° line by virtue of the characteristics of the antenna for desired conditions and therefore are not shown on the drawings.

On the basis of the above discussion, it would follow that the proper place to locate the auxiliary radiators is at or near the edges of the wings. If a low signal is to be obtained over as wide an angle as possible, the combined pattern of the two cancelling elements should track the pattern of the Huygens' sources as closely as possible. This can be accomplished when the spacing between the two cancelling elements is made equal to the effective electrical spacing of the Huygens' sources. Then, if the cancelling elements are fed so as to produce the field of the same amplitude as that in the back lobe, but in reversed phase, it would be expected that the field in the rear drop to vary low values over a wide angle.

It will be noted from the discussion in the specification below, the position of the auxiliary radiators is critical if a substantial reduction in the back lobe for a wide sector is desired. The apparent spacing of the Huygens' sources is considerably greater than the physical spacing between

the outward edges of the wings. It is therefore necessary for an effective reduced back radiation to position the rear cylinders beyond the edge of the wings. Various methods of feeding the antenna of the present invention may be employed and the structure may comprise a number of repeated sections depending upon the power which the antenna is to handle.

The present invention will be more fully described and the principles of its operation more fully analyzed and explained in the specification below when taken in connection with the drawings illustrating an embodiment of the same, in which:

Figure 1 shows a simplified form of the antenna structure alone as viewed from a front elevation in which the greater portion of the radiation is directed.

Figure 2 shows a rear elevation of the antenna of Figure 1.

Figure 3 shows a plan view of Figure 2 as viewed from the top.

Figure 4 shows a plurality of antennae of Figure 1 employing a slot with closed ends in a vertical array.

Figure 5 shows a relative amplitude pattern in azimuth angles for the radiator of the type shown in Figure 3.

Figure 6 in polar coordinates with the same cylinder and the two auxiliary side cylinders taken alone.

Figure 7 shows a pattern in polar coordinates taken of an antenna structure where the auxiliary slotted cylinders were fastened to the wings of the main antenna, and,

Figure 8 shows the pattern of the antenna for the structure providing the curve of Figure 7 where the patterns of the rear cylinders and the front cylinders were taken separately.

The general arrangement of the antenna will be seen from the drawings. Referring more particularly to Figures 1, 2 and 3, it will be noted that the main unit consists of a conducting cylinder 1 having a gap 2 with conducting side wings 3 and 4 extending tangentially from the cylinder near the gap at an angle slightly backwards from the horizontal. Taking the line B of symmetry backwards as 180° in a backward direction, the angle A to the wings may be approximately 70°. The cylinder 1 may vary in shape from that of a pure cylinder in the general manner that has been previously pointed out in some of my prior applications, referring particularly to my application Serial No. 694,319, filed August 31, 1946. Such variations may include figures symmetrical about a central axis and figures having an axis of symmetry with the plane. The size of the cylinder and the size of the wings may vary of course with the operating frequency and in general the lower the frequency the larger will be the dimension of the antenna. The auxiliary radiators may comprise cylinders 5 and 6 of the same general design as cylinder 1. These are provided with air or insulated gaps 7 and 8 respectively which face backward in the direction of the axis B. The cylinders are positioned in the vicinity of the outer edges of the wings. If the wings 3 and 4 are continued the cylinders will preferably be tangential to the planes of the wings a short distance beyond the normal wing lengths in most cases. These slots are usually covered with a sheet of insulating material to keep out ice. The reason for this will be explained later. In the use of an open or insulated antenna slot such as shown in Figures 1, 2 and 3, the an-

tenna may be fed at one end by coaxial cables 9, 10 and 11 as indicated. The inner conductor of the cable is connected to one side of the gap and the outer conductor is connected to the other side of the gap. To the main cylinder 1 is fed the major portion of the power and to the auxiliary cylinders 5 and 6 is fed an auxiliary current whose phase and amplitude will be adjusted to produce the desired annulling or compensating effect to reduce the backward rotation pattern as will be presently indicated.

In the arrangement indicated in Figure 4 where a group of two units are used as is indicated by 12, 13, the cylinder slots 15, 16 and 17 are shown as closed and slots and may therefore be fed by a feed at the center from coaxial cables 19, 19', 20, 20' and 21, 21'. Means 14 are provided for adjusting the phase and relative amplitude fed to the auxiliary cylinders while the main cylinders are fed through the cable 40 connected to the junction box 41 from which cables 20 and 20' lead.

An insight into the position of the auxiliary cylinders is shown by the curves of Figures 7 and 8.

The pattern of Figure 7 was obtained with a model antenna operating at 2,000 mc. The two slotted cylinders in this case were fastened to the back side of the wings with the slots facing to the rear and all three cylinder elements were driven with the two rear cylinders properly adjusted to give a minimum of radiation at 180°. The null indicated in Figure 7 by the dotted line curve in the polar diagram is deep but does not extend over as large an angle as is desired. The reason for this difficulty becomes clear on an examination of Figure 8. In this figure the curve 22 is the pattern of the front cylinder with the wings, while the dotted curve 23 is the pattern of the two auxiliary rear cylinders fed independently of the front cylinder. The two patterns track only over an angle of about 20°. A closer examination, as has been stated above, shows that the apparent spacing of the Huygens' sources is considerably greater than the physical spacing of the two rear cylinders in this arrangement. The effective phase centers of the Huygens' sources are not at the edges of the wings but are beyond them.

As contrasted with the curves of Figures 7 and 8, the curves of Figures 5 and 6 show a more desirable pattern in the polar diagram of Figure 6 which corresponds in general to the preferable arrangement of Figure 3. The pattern 25 is for the front cylinder with the wings and the pattern 26 is for the rear cylinders. It is clear that the tracking in the rear sector of the pattern is quite close over a wide angle. In Figure 5 a curve is shown with a plot of relative amplitudes as ordinates and the azimuth directions plotted as abscissae. The dotted curve 30 represents the desired protection in the desired sector. This is a curve based on normal requirements and is defined in the table below based on an R. M. S. value of field which as indicated is 690 mv.

TABLE
[R. M. S. value of field 690 mv.]

Azimuth	E-mv.
180°	20
170°, 190°	20
160°, 200°	30
150°, 210°	50
140°, 220°	115
130°, 230°	225

The curve 31 shows the back sector radiation corresponding to the curve taken in Figure 6 and shows substantial compliance with the desired pattern. In Figure 5 the minimum amplitude of back direction occurs at approximately 12° on either side of 180°.

The relative power for the main and auxiliary cylinders may be obtained from the curves of Figure 6. The amplitudes of the two patterns in Figure 6 are adjusted so that they are equal at 180°. By integrating the two patterns it is found that the two rear cylinders together require $\frac{1}{3}$ as much power as the main cylinder. The rear cylinders therefore will be energized in this ratio in opposite phase to that of the main cylinder.

Since the presence of the auxiliary cylinders in the field causes some irregularities in the radiation from the wing edges it is not too practical to determine the position of the auxiliary cylinders wholly by calculation. Experimental patterns should be obtained on a model at correspondingly high frequency, to determine the position of the cylinders more exactly for the desired pattern of radiation. The relative dimension given in Figure 3 we obtained by such experimental procedure and may, therefore, be used. It should be added that when great accuracy of pattern is desired the effect of relatively small fillings located in the field of the radiation may become appreciable so that care in engineering design is necessary.

Having described my invention I now claim:

1. An ultra high frequency antenna comprising a main unit formed as a conducting cylinder having a slot extending longitudinally thereof with conducting wings extending from the outer surface of the cylinder outwards at each side of said slot, the outer edges of said conducting wings running substantially parallel to said slot and adapted to form Huygens' radiation sources when said slot is energized by high frequency waves, a pair of auxiliary conducting units parallel to the axis of the slotted cylinder positioned near but beyond the ends of said wings in positions equal to the effective electrical spacing of the Huygens' sources from said slot, and means for feeding said auxiliary conducting units for producing fields of substantially the same amplitudes in reversed phase as said Huygens' radiation sources, whereby a composite radiation pattern substantially of a cardioid figure with a null in the direction of diametrical symmetry of the antenna will be obtained.

2. An arrangement as in claim 1 in which said auxiliary conducting units comprise a pair of conducting cylinders each having a slot extending longitudinally thereof.

3. An arrangement as in claim 1 in which said main unit has its slot electrically shorted at both ends.

4. An arrangement as in claim 2 in which said main and auxiliary units have their slots electrically shorted at both ends.

5. An arrangement as in claim 2 in which the slots in the auxiliary cylinders face in the opposite direction from the slot in the main cylinder.

6. An ultra high frequency antenna comprising a main unit formed as a conducting cylinder having a closed ended slot extending parallel to the axis thereof with outwardly and backwardly extending conducting wings extending from the outer surface of the cylinder at each side of said slot, having a diametrical axis of symmetry through the axis of said cylinder, a pair of auxiliary cylinders positioned beyond the ends of the wings, each auxiliary cylinder having a closed ended slot parallel to the axis thereof and to each other and the main cylinder, the slot of the main cylinder facing forward of the wings and the slots of the auxiliary cylinders facing backward.

7. An arrangement as in claim 6 including means for feeding said cylinders across the slots.

8. An arrangement as in claim 6 including means for feeding said cylinders across the ends of the slots therein.

9. An arrangement as in claim 6 including means for feeding said cylinders across the middle of the slots therein.

10. An arrangement as in claim 6 including means for feeding the main cylinder and the auxiliary cylinders separately, the latter with a fraction of the power supplied to the main cylinder in the reverse phase for substantially annulling a part of the backward lobe produced by the main cylinder alone.

11. An arrangement as in claim 6 including means for feeding the main cylinder and the auxiliary cylinders separately, the latter with a fraction of the power supplied to the main cylinder in the reverse phase for producing a composite radiation pattern substantially of a cardioid figure with a null in the direction of the diametrical symmetry of the antenna.

12. An arrangement as in claim 6 in which the cylinders and wings reoccur in repeated sections with corresponding elements in substantial alignment and means for feeding each of said cylinders with ultra high frequency.

ANDREW ALFORD.
